UNITED STATES PATENT OFFICE.

ANDREW EPPLER, OF LYNN, MASSACHUSETTS, ASSIGNOR TO UNITED SHOE MACHINERY COMPANY, OF PATERSON, NEW JERSEY, A CORPORATION OF NEW JERSEY.

WELT-WINDING MACHINE.

1,141,449.

Specification of Letters Patent.

Patented June 1, 1915.

Application filed August 1, 1910. Serial No. 574,966

To all whom it may concern:

Be it known that I, ANDREW EPPLER, a citizen of the United States, residing at Lynn, in the county of Essex and State of Massachusetts, have invented certain new and useful Improvements in Welt-Winding Machines; and I do hereby declare the following to be a full, clear, and exact description of the invention, such as will enable others skilled in the art to which it appertains to make and use the same.

The present invention relates to certain new and useful improvements in welt winding machines.

In the manufacture of welted shoes, the welt is prepared by being first cut into strips, and passed through a grooving and beveling machine, then thoroughly moistened, after which it is ready to be fastened to the shoe. After the strip of welt has been passed through the grooving and beveling machine, it is coiled into a loose skein by the operator in order that it may be more conveniently immersed in the water. It is customary, when forming this skein by hand, for the operator to give the strip of welt a complete twist for each revolution of the skein. The necessity for doing this will be easily seen when it is considered that as the welt is being applied to the shoe the skein is laid upon the floor and a length of the welt is drawn up from the skein. If an initial twist in the opposite direction were not put in the welt it would twist and form kinks at this time, seriously interfering with the work of the operator.

The object of this invention is to wind the strip of welting into a loose coil or skein as it comes from the groover and beveler and to automatically give the strip of welting the proper amount of twist in order that it shall unwind properly when the operator is applying it to the shoe.

A further object of the invention is to provide a reel over which the welt may be wound and from which the welt may be easily removed at the conclusion of the winding operation.

Still further objects of the invention are to provide improvements in the various details of the winding machine tending to increase the efficiency and better the mode of operation of the machine.

With the above ends, one feature of the invention contemplates the provision of a

winding reel which revolves in a curved path about an axis substantially at right angles to its own axis, about which it is rotated, in order that the strip of welting may be twisted and at the same time wound into a coil or skein.

A further feature of the invention comprises a collapsible reel which holds the strip of welting in proper position during the winding operation but which may be collapsed to remove the coil of welting at the conclusion of the winding operation.

Still further features of the invention will be more fully described in the following specification.

In the accompanying drawings, illustrating the preferred form of the invention, Figure 1 illustrates a side elevation of the welt winder with a portion of the frame cut away and shown in section; Fig. 2 is a detail showing a plan view of the collapsible reel looking down upon the same from above, Fig. 3 is a sectional detail illustrating the operating mechanism for collapsing the reel, Fig. 4 is a sectional detail showing the arrangement of the parts for collapsing the reel and for rotating the same, and Fig. 5 is a diagrammatic view showing the course of the strip of welting as it is drawn by the welt winder from the power groover and beveler.

In the illustrated embodiment of the invention, the winding reel 1 is rotatably mounted on a head 2 which is supported upon one end of the main driving shaft 3 of the machine. The welt winding machine is positioned a short distance away from the groover and beveler 4 and in order that the strip of welting may be wound properly upon the winding reel 1, it is preferred that the movement of the winding reel 1 in a curved path shall generate the surface of a cone of which the point of delivery of the groover and beveler is the apex, as illustrated clearly in Fig. 5. To accomplish the above result the winding reel 1 is rotated about an axis substantially at right angles to the axis of the shaft 3 but preferably slightly inclined thereto in order that the curved path of the winding reel and the strip of welting leading to it shall generate the surface of the cone.

As it would be difficult to so accurately gage the speeds of the winding machine and the groover and beveler that they would be

exactly alike at all times and as the speed with which the strip of welting is wound upon the reel increases as the diameter of the coil or skein of welting increases, it is deemed advisable to drive the welt winder at a slightly greater speed than the grooving and beveling machine and to provide a yielding driving connection in order that a certain amount of slip will occur when the tension upon the strip of welting becomes too great. The power is delivered from an exterior source to the main drive pulley 5 which is loosely mounted upon the driving shaft 3. The drive pulley is locked to the shaft 3 through the engagement of the friction disk 6 mounted upon one side of the drive pulley and the friction disk 7 keyed to the end of the shaft 3. The friction disks are engaged with one another by moving the drive pulley 5 longitudinally of the shaft 3 by means of the sliding collar 8. The collar 8 is operated by a bell crank lever 9 pivotally mounted in the frame 10 of the machine and having one end fastened to the collar 8 and having the other end engaged by a coiled spring 11. The coiled spring 11 is a compression spring and bears at one end against the lower end of the bell crank 9 and at its opposite end bears against a normally fixed screw 12 held in position by a lock nut 13. The tension of the spring may be varied, by adjusting the screw 12 in the frame 10. The normal action of the spring is to force the friction disks 6 and 7, comprising the clutch, into engagement with one another and lock the drive pulley to the shaft. A wedge block 14 is mounted upon the end of the shaft 16 and bears against the lower end of the bell crank 9 to move the bell crank against the action of the spring 11 in order to disengage the friction disks 6 and 7 and unlock the pulley 5 from the shaft 3.

The winding reel 1 is rotated about its own axis by the beveled gear 17 engaging with the bevel gear 18 sleeved upon the shaft 3 and locked against rotation relatively to the frame 10 by the pin 19. The beveled gear 17 is keyed to the lower end of the hollow shaft 20, which is mounted for rotation in the head 2, and has the winding reel 1 fastened to its upper end. It will thus be seen that as the main driving shaft is rotated the head 2 mounted upon the outer end of the shaft will rotate and cause the winding reel 1 to revolve in a circular path while at the same time the engagement of the gears 17 and 18 will rotate the winding reel about the axis of the shaft 20. The compound movement which is thus generated will give the proper twist to the strip of welting as it is wound. The winding reel proper comprises a base 21 having a plurality of arms 22 pivotally mounted upon it. In order that the skein of welting may be

easily removed from the reel after it is wound thereon, means is provided for collapsing the reel or moving the arms inwardly toward one another. The arms 22 are connected by links 23 with a central collar 24 which threadedly engages a screw 25. When the screw 25 is rotated to cause movement of the collar 24 in a vertical direction, the links 23 will draw the arms 22 inwardly owing to the fact that the arms 22 have their lower ends pivotally mounted below the point of connection of the links 23 with the arms and the skein may be then easily slipped from the reel. The end of the skein is fastened to the arms 22 at the beginning of the winding operation by providing a series of spring clips 26, one of which is mounted upon each arm and between which and the arm the end of the welting may be held. A rotation of the screw 25, in order to collapse the reel, is secured by mounting the screw upon the end of a shaft 27 which is rotatably mounted in the hollow shaft 20 and has a hand wheel 28 fastened to its lower end in order that the operator may conveniently rotate the screw 25. A stop in the form of a flat disk 29 projecting beyond the threads of the screw 25 is attached to the upper end of the screw and limits the movement of the collar 24 in one direction.

It is considered preferable to provide a guide which shall properly guide the strip of welting as it is wound upon the reel and which shall prevent the end of the strip from flapping about as it comes from the groover and beveler, loosening up and unwinding the coils of welting which have been already wound upon the reel. The guide yieldably presses against the strip of welting so that the twist which is placed in it will pass under the guide and it may be stated at this time that although one twist may not occur in every convolution of the welting, if the twist is omitted in one convolution there will be a double twist in the following convolution and in this way the total amount of necessary twist is imparted to the welt and inasmuch as there is a considerable length of welting unwound from the skein as the operator applies it to the shoe, the welting will always come to the operator in a straight form. The guide, which is provided in the present instance for maintaining the strip of welting in proper position, comprises an L-shaped bar 30 having one side positioned adjacent and parallel to the fingers 22 as the reel rotates. The bar 30 is fastened in a block 31 loosely mounted upon the stud 32. The guide is held in yielding engagement with the strip of welting by a coiled spring 33 which engages the block 31 at one end and a fixed collar 34 at the other end. The bar 30 is held in proper position when the machine is inoperative by a pin 35 which is mounted upon the outer

end of the supporting bracket 36 and has its upper end engaging with the rear end of one side of the bar 30. The guide, as a whole, is mounted upon the supporting bracket 36 which is attached to the head 2 and travels in a circular path with the reel.

While the particulars described are well suited to one mechanical form of the invention, it is not to be understood that these 10 particulars are essential since they may be variously modified within the skill of the artisan without departing from the true scope of the actual invention as defined by the claims.

15 What is claimed, is:—

1. A welt winding machine, having, in combination, a rotary winding reel having a plurality of arms, mechanism for rotating the reel, a guide arm permanently supported 20 parallel to the axis of rotation of the reel, and means for yieldingly maintaining the arm in operative relation to the reel to permit the strip of welting to be wound and bind the strip tightly to the reel.

25 2. A welt winding machine, having, in combination, a rotary winding reel comprising a plurality of arms, the winding reel adapted to revolve about an axis substantially at right angles to the axis about which 30 it rotates and a guide yieldably mounted adjacent to the winding reel and adapted to revolve with the reel, the guide being parallel to the arms of the reel and pressing against the strip of welting as it is wound 35 upon the reel, and a stop to limit the movement of the guide when the winder is inoperative, substantially as described.

3. A welt winding machine, having, in combination, a drive shaft, a winding reel supported upon one end of the drive shaft 40 with its axis substantially at right angles to the axis of the drive shaft, means for rotating the reel about its own axis as the drive shaft is rotated, and a clutch connected to the drive shaft and arranged to slip when 45 the tension upon the welt exceeds a predetermined amount, substantially as described.

4. A welt winding machine, having, in combination, a winding reel, means for rotating the winding reel in a circular path 50 substantially at right angles to the axis of rotation to impart a uniform twist to the strip of welt as it is wound, and driving mechanism arranged to allow the movements of the reel to slow down when the tension 55 upon the welt exceeds a predetermined amount while maintaining a constant ratio of twist, substantially as described.

5. A welt winding machine, having, in combination, a winding reel arranged to 60 wind a strip of welting from an exterior point, means for revolving the reel in a circular path to impart a twist to the welt as it is wound, and means for simultaneously rotating the reel about an axis inclined to the 65 axis of revolution in order to cause the strip of welting to generate the surface of the cone and wind evenly upon the reel, substantially as described.
